Primary Examiner — Sanjeev Paul(74) Attorney, Agent, or Firm — Steven A. Nielsen; www.NielsenPatents.com(57) CLAIM

The ornamental design for a mini bench towel, as shown and described.

DESCRIPTION

FIG. 1 is a top view of a mini bench towel showing my new design; and,

FIG. 2 is a bottom view thereof.

The broken lines of figure 1 and 2 showing stitching are included for the purpose of illustrating environmental subject matter only and form no part of the claimed design.

1 Claim, 2 Drawing Sheets(56)
